TRIPOD OR THE LIKE

Original Filed Sept. 21, 1929

FIG. 1.

JAMES G. McLEISH,
INVENTOR.

BY *Harold C. Shipman*
ATTORNEY

UNITED STATES PATENT OFFICE

JAMES GEORGE McLEISH, OF IRVINE, ALBERTA, CANADA

TRIPOD OR THE LIKE

Application filed September 21, 1929, Serial No. 394,348, and in Canada January 12, 1929. Renewed November 21, 1930.

This invention relates to tripods or the like and my invention has for its principal object the provision of a structure which is of such a nature that it can be manufactured at a most reasonable cost and yet provides a structure which is most efficient when in use.

A further object is to provide a tripod or the like which embodies a structure wherein the legs may be detachably connected to a head, thus facilitating the handling of such structure.

With the foregoing and other objects in view, as will appear as the description proceeds the invention consists of the novel construction, combination and arrangement of co-operating elements as hereinafter more specifically set forth, claimed and shown in the accompanying drawings forming a part of the present application, in which:

20 Fig. 1 is a perspective view of the preferred embodiment of my invention.

Fig. 2 is an enlarged detail view of a modified form.

Fig. 3 is a perspective detail view of the connecting member.

Like numerals of reference designate corresponding parts throughout the different views.

4 is a head plate preferably having three long sides 5, 6 and 7, which sides have their edges rolled to cover around the reinforcing bar 8. Intermediate the ends of the rolled sides 5, 6 and 7, I provide cutout portions so as to permit the straps 9 to engage around the reinforcing bar 8 at its respective points. The straps 9 are securely attached to the upper ends of the legs 10 by means of screws or bolts 11. The head plate 4 is provided with a central opening through which an engagement member 12 may be supported from the plate 4 and to which a block and tackle or any other lifting mechanism may be attached.

Referring to Figs. 2 and 3, showing the modified form of the connecting member 14 which is substituted for the straps 9, the body portion of the connecting member is securely attached to the upper ends of the legs 10 similar to the strap 9. The inner portion of the connecting member 14 is cut longitudinally 50 to form a tongue which is bent upwardly as at

15 to provide an engagement member having a curved upper end. The intermediate portion 16 of the connecting member 14 is grooved transversely to provide a seat in which the reinforcing bar 8 will normally be seated. By swinging the free ends of the legs 10 around and lowering the leg simultaneously the hooked end of the tongues 15 may be removed from their lapped engagement around the reinforcing bar 8 and the respective legs removed.

The foregoing specification and annexed drawings disclose the preferred embodiment of my invention but it is to be understood that minor changes may be resorted to in the commercial adaptation of my invention without departing from the scope of the invention as hereinafter claimed.

What I claim as new is:

1. A tripod structure comprising in combination a head member; a reinforcing bar; legs hingedly connected to said reinforcing bar; a block and tackle supporting member supported downwardly from said head member; major portions of the edges of said head member being lapped around said reinforcing bar; strap members hingedly lapped around said reinforcing bar intermediate said portions and connected to the upper ends of said legs.

2. A tripod structure comprising in combination a head member; a reinforcing bar; removable legs hingedly connected to said reinforcing bar; a block and tackle supporting member supported downwardly from said head member; major portions of the edges of said head member being lapped around said reinforcing bar; strap members hingedly lapped around said reinforcing bar intermediate said portions and connected to the upper ends of said legs; a portion of said strap member extending upward in hook-shaped formation adapted to engage said reinforcing bar while said legs are being swung to disengaged position and the intermediate portion of said strap member being formed to provide a sunken seat for said reinforcing bar.

In testimony whereof, I affix my signature.

JAMES GEORGE McLEISH. 100
